ELASTIC BELT

Suzanne Poirier and Israil Michel Juzenka,
Liege, Belgium

Application May 21, 1954, Serial No. 431,512

Claims priority, application Belgium June 2, 1953

2 Claims. (Cl. 2—43)

The invention relates to elastic belts, and particularly to suspender belts, corsets, or surgical wear of a like nature, comprising an elastic part constituting the back and the sides, and a panel of non-elastic material constituting the front of the belt, a reinforced strip extending from one lateral edge of the front panel around the back to the other lateral edge. 15

One of the greatest difficulties to be overcome in belts of the kinds described, if they are to give complete satisfaction, is to provide an adequate support for, or restraining pressure, on the abdomen without compressing 25 the stomach.

A number of methods of construction have previously been proposed some of which do not provide sufficient support, while others compress the stomach thus causing inconvenience to the wearer. It is among the objects 30 of the present invention to avoid these undesirable effects and to provide a belt which provides maximum possible comfort in wear.

To this end, in the belt according to the invention, there is provided a reinforcement strip intended to be placed in an elastic belt, said belt being constituted by a front panel of non-elastic fabric connected at its side edges to a panel of elastic fabric constituting the back and sides of the belt, said reinforcement strip being constituted by an elastic fabric of generally trapezoidal shape, the lower edge of which is a sinusoidal curve, and which is attached to the elastic part of the belt so that the narrowest part of the reinforcement strip is in the middle of the back at the waist of the belt, and as it extends towards the front of the belt increases gradually 40 downwardly in height, the highest part being joined to the side edges of the non-elastic front panel which allows flattening the abdomen by a traction independent of the belt proper.

In one construction according to the invention, the reinforced strip is preferably secured on the inner surface of the said elastic part as by stitching along the waist-line of the belt.

An alternative and equally advantageous construction incorporates a reinforced strip which is formed by an elastic piece of a stronger quality, but of less elasticity than the elastic part, the strip being inserted to replace a cut-out portion of suitable shape in the elastic part and secured thereto, preferably by stitching.

The invention is hereinafter described by way of example with reference to the accompanying drawings, in which:

Figure 1 is a perspective view of a belt according to the invention arranged inside out to show the inner panels of the garment;

Figure 2 shows, outstretched, the shape of the reinforcing strip, and

Figure 3 is a modification of a belt according to Figure 1, only the upper part of the belt being shown.

The same reference numbers are used in all Figures 70 to designate the same or similar parts.

The belt illustrated in Figure 1 comprises an outer

2

elastic part 1 constituting in known manner the back and the sides of the belt. The said part 1 is made up from several panels of material cut in an appropriate manner so that the assembled part follows the contours of the body. The front 2 of the belt is a panel of woven material secured at the lateral edges of the elastic part 1. Reinforcing strips 6 are provided in both the front panel and part 1.

A reinforcing strip 3 made of elastic material, which 10 may be the same as that employed for the part 1, is secured to the inner surface of the part 1. The reinforcing panel 3 is delimited at the top by the waist-line 4 of the belt, and is shaped substantially as illustrated in Figure 2, being stitched to the part 1 along the waist-line 4. A mid-position of the back, the strip 3 has a relatively reduced width *a* which may measure from 2 to 12 centimeters, the width increasing gradually from the middle of the back to the position at which it joins the lateral edges of the front panel 2. At the position at which it joins the front panel 2, the width *b*, of the reinforcing panel may be between 12 and 25 centimeters.

The belt illustrated in Figure 1 may be stretchable above the waist as well as in the back and at the front. The part 5 is comprised in the elastic part 1 above the waist-line 4 and is made from an ordinary elastic material. Thus there are two thicknesses of elastic material only below the waist-line 4. As a result the belt provides greater support or tension in the area of the abdomen than in the area of the stomach which is thus not uncomfortably compressed. Furthermore, since the part 5 can be more readily stretched than the area of the reinforcing strip 3, the construction provides that when the belt is worn by people who are a little stout, the formation of swelling or bulges does not occur above the belt. One of the objects of the invention is thus achieved, that is to say, the belt serves to provide correct support for the abdomen without compressing the stomach.

Figure 3 shows a modification in which the belt at mid-position of the back does not stretch above the waist. 40 As a result the part 5 is reduced in size and exists only at each side of the belt near the panel 2. In this alternative construction also the reinforcing strip 3 is delimited by the waist-line 4 so that uncomfortable and undesirable compression of the stomach is avoided.

In the two constructions illustrated, the reinforcing strip 3 is not interrupted in the middle of the back so that the back portion of the panel does not stretch too much under the effect of the tension exerted on it whilst supporting the abdomen.

Furthermore, the belts may be constructed so as to include an unbacked reinforcing strip 3, of the shape illustrated in Figure 2, which is made from an elastic material of stronger quality, that is to say, material of inferior elasticity, than that from which the elastic part 1 is formed. For this purpose the back and side parts of the outer part 1 are reduced in width and altered in shape to conform along the top edge with the shape of the reinforcing strip 3, which is then secured as by stitching directly on to the lateral edges of the front panel 2 and to the upper edges of the elastic portion 1. In this construction, in which the reinforced zone of the belt is not double, the reinforcement obtained results from the quality of the material used to form the strip 3 of the garment.

65 It is to be understood that the invention is by no means limited to the construction hereinbefore described, and that it is possible still further to modify these constructions within the scope of the claims hereunder. Thus for example the reinforcing strip 3 may be provided on the external surface of the part 1, or the reinforcing strip 3, which is illustrated in Figure 2 as being made in one piece, may be made by joining two or more pieces of

material by a seam or seams in mid-position of the back, as by stitching.

We claim:

1. In an elastic belt comprised of a front panel of non-elastic fabric and a panel of elastic fabric constituting the back and sides of the belt, the side edges of the panels being attached, that improvement comprising a reinforcement strip of elastic fabric having a generally trapezoidal shape, the lower edge of which is in the form of a sinusoidal curve, said strip attached to the elastic fabric of said belt with the narrowest part of said strip at the middle of the back at the waist of the belt and as it extends towards the front of the belt increases gradually downwardly in height, the highest part being joined to the side edges of the non-elastic front panel, which allows 15 flattening the abdomen by a traction independent of the belt proper.

2. The improvement as claimed in claim 1 in which the panel of elastic fabric has an opening therein with the same shape as said reinforcement strip and said strip is attached to the elastic fabric along the edges of said opening.
